[57] CLAIM

The ornamental design for a glass, as shown and described.

DESCRIPTION

FIG. 1 is a perspective view of a glass showing my new design;

FIG. 2 is an elevation view of the figure taken on any side thereof; and

FIG. 3 is an end view showing the lower end of the FIG. 2, the top end thereof being a plain annulus of a circle.

FIG. 1

FIG. 2

FIG. 3
